ABSTRACT

This invention comprises a settling tank of the type in which is incorporated a built-in settling trough or chamber. The invention also includes within its scope an improved process of building such tanks with pre-cast panels in accordance with sound engineering practice and in a manner that is advantageous from the standpoint of expense and durability.

COMPOSITE SEWAGE TANK

The tank of this invention may be constructed of panels precast and initially assembled in circular or other closed formation with upright longitudinal channels or slots located between adjacent panels or spaced with respect to certain of them. These channels are subsequently filled and closed from top to bottom of the tank with cement or mortar and at an intermediate level certain panels contain inwardly projecting cantilever spoke sections or knees. These corbel units act collectively as fully efficient brackets upon which may now be supported a circular settling chamber or trough. The inner wall of this trough forms a circular weir over which the liquid effluent flows into the trough. The corbel units may be cast at any selected level within the tank with the assistance of temporary forms. The bottom and side wall or walls of the effluent trough may be readily cast upon the firm foundation of the corbels.

The effluent trough may be formed in part by the core wall of the tank itself or it may be located at a distance from the inner tank wall so that weir overflow takes place at both circumferential walls of the trough.

The panels may be precast upon metal sheathing as described in my prior U.S. Pat. No. 3,280,525 Oct. 25, 1966. The tank as a whole may be prestressed by winding with wire or metal cable in position to enclose the corbel units and finally a cemetitious cover coating for the prestressing wire may be applied.

A feature of the invention in which sound engineering principles of concrete construction are put into effect is achieved by employing cantilever sections inclined inwardly and upwardly in cone-like arrangement within the tank. In such a construction the entire weight of the effluent trough and its liquid contents are transmitted as compression to the corbel spokes. Thus both the spokes and the effluent trough are maintained in a state of continuous compression.

These and other features of the invention will be more readily understood from the following description of preferred embodiments thereof, selected for purposes of illustration and shown in the accompanying drawings, in which

FIG. 1 is a view in perspective of a quarter section of the core wall;

FIG. 2 is a fragmentary sectional view of the wall;

FIGS. 3 and 4 are corresponding views of a modified tank construction.

In the tank of FIGS. 1 and 2 each panel 10 is represented as precast upon metal sheathing 11 which forms the outer surface of the precast core wall. These panels 10 are assembled and erected to form the cylindrical core wall of the tank, and may be located underground in an adequate excavation.

In assembling the panels 10 open channels 12 are dispersed between them for the reception of corbel units. These inserted units completely fill and cover the open channels and form solid bars 13. The corbel units 14 are triangular in shape and reinforced with wires or rods 15. Each of them includes a horizontally disposed top surface and upon this rests the bottom 16 of the effluent trough. By reason of their triangular shape the corbel units include cantilever sections which incline inwardly and upwardly in the tank giving the whole assembly the resemblance of a shallow upwardly convex

cone. It is apparent therefore that the full weight of the trough is supported as compression by the cantilever section of the corbel units. This pressure therefore subjects the arms to continuous pressure above anything encountered in the operation of the tank.

The effluent trough is completed by an inner wall 17 which acts as an inlet weir for the trough. As shown in FIGS. 1 and 2 the outer wall of the trough is formed by the inner surface of the core wall of the tank while the inner wall 17 of the trough may be cast integral with the bottom 16. At a convenient place the trough may be provided with an outlet pipe 30 through which the contents of the trough may be drained for further treatment without encountering disturbance that would tend to float the solid contents of the effluent.

In FIGS. 3 and 4 is illustrated a tank of modified construction in which the effluent trough as a whole is offset inwardly and spaced with respect to the core wall so that the outer wall 29 will serve as an additional inlet 20 weir, thus substantially increasing the weir length as compared to that of the tank shown in FIGS. 1 and 2.

The panels 20 are separated by channels 22 which are later filled with solidified corbel units 23. Each corbel unit is provided with a spoke 25 extending upwardly and inwardly to the bottom of the effluent trough 27. The effluent trough is completed by an inner wall 28 and an outer wall 29. The trough is provided at a convenient location with an outlet pipe 30 by which the effluent may be drained from the trough. The clamping section 24 is extended upwardly to a ring or flange which retains the trough in true concentric location. The lower ends of the spokes 25 extend to the core wall near the bottom of the tank and are confined by binding with prestressed wire 32 which thus is arranged to confine the outward pressure transmitted by the spokes 25.

It is apparent that by locating the assembled cone-like structure at a convenient height above the footing 31 of the core wall the bottom of the tank is left entirely free of obstructions that would hinder the free passage of a sludge scraper or plow rotating on the floor of the tank.

The coil of wire 32 forms a tension band embracing the outer ends of the corbel spokes, while the flange or ring 32 forms a compression band embracing the upper ends of the spokes.

The corbel units may be of any desired width. In fact they may be of the full width of the panels 10, although a width of 12 to 14 inches is usually adequate and more convenient for construction of a tank upon its permanent site.

I claim:

1. A settling tank having an outer circular wall of precast concrete panels, cast-in-place concrete filler joints between said panels, said wall being constructed and arranged upon a floor for said tank, metal tension members encircling the exterior of said circular wall, concrete structural members each with a first end and a second end supporting an effluent trough within said tank, said first end of each said structural member being connected to a filler joint and integral therewith, said structural members being inclined inwardly and upwardly whereby said second ends are higher than said first ends whereby the weight of the trough is transmitted to the structural members to place said structural members in compression.

2. A settling tank as described in claim 1, wherein the effluent trough has inner and outer walls which are spaced from the inner surface of the wall sufficiently for both the inner and the outer walls of the trough to act as weirs.

3. A settling tank as described in claim 1, wherein the effluent trough is mounted concentrically within the wall of the tank by said concrete structural members under compression having inwardly and upwardly inclined sections confined at their upper ends by the 10

trough in a state of compression and at their lower ends by a tension ring.

4. A settling tank as described in claim 3, wherein the tension ring at the lower ends of the inclined sections is prestressed.

5. The tank of claim 2 in which the trough and said concrete structural members are maintained in compression.
